UNITED STATES PATENT OFFICE.

GEORGE T. JOHNSON AND HARRY W. STERTZBACH, OF COLUMBUS, OHIO, ASSIGNEES
TO THE BUCKEYE STEEL CASTINGS COMPANY, OF COLUMBUS, OHIO.

CAST CAR-TRUCK SIDE FRAME.

Application filed March 25, 1926. Serial No. 97,340.

This invention relates to car trucks and has special reference to side frames of the type disclosed in Letters Patent No. 1,523,793, granted January 20th, 1925, to

5 H. W. Stertzbach and M. R. Hansen, in which the entire frame, including the journal boxes, is an integral casting and the compression and tension members are in the form of inverted channels extending from 10 the columns to the tops of the journal boxes. The object of the present invention is to provide a construction which will tie together the side walls of the compression member in the region of the journal box 15 and overcome the buckling tendency which results from the compression and shearing stresses. The invention is illustrated in the accompanying drawing and will be hereinafter fully described and particularly de- 20 fined.

In the drawing, Figure 1 is an elevation of a side frame embodying the present invention;

25 Figure 2 is a top plan view of the same; Figure 3 is a section on the line 3—3 of Fig. 2;

Figure 4 is a view similar to Fig. 3 but showing a slightly different form of the central rib.

30 In the drawing, the reference numeral 1 indicates one of the columns of the side frame, 2 the compression member, 3 the tension member, and 4 the journal box, the compression and tension members being inverted channels extending from the top and bottom of the column to the top of the journal box. The side walls of the compression and tension members are united with the journal box and the top 35 of the compression member is extended over the top of the journal although preferably cut away at its extremity as at 6, to reduce weight. The top plate 7 of the tension member does not extend entirely to the journal

40 box but terminates in an upwardly curved web 8 which follows the edges of the side walls of the compression member in the region of the journal box and unites the walls, said connecting web terminating at

the straight edges of said walls which extend to the column 1. The side walls of the tension and compression members are thus united in the region of the journal box so that they will effectively resist the tendency to buckle due to the compression and shearing stresses, while the open space at 9 between the journal box and the web 8 is advantageous in accommodating shrinkage in the process of manufacture.

45 Preferably, a central longitudinal connecting and bracing rib, shown at 10 in Fig. 3 and at 11 in Fig. 4, is provided over the inner portion of the top of the journal box to connect the same with the top of the compression member and also with the web 55 8. The rib 10 has its lower edge arranged to span the space 9 approximately in the plane of the top of the journal box but the rib 11 is elongated so as to extend down in the space 9 and divide the same, the lower 60 edge of this form of rib being close to the bottom of the tension member. It will be noted that the longer rib 11 braces the sides, as well as the top, of the journal box without destroying the advantageous space 9.

65 The side walls of the compression member are connected by metal which is an essential element of the frame and not a mere accessory having only the function of a tie.

70 Having fully described our invention 80 what we claim as new and desire to secure by Letters Patent, is:—

75 1. A cast side frame for car trucks having a compression member, a tension member, and a journal box, the compression and tension members having the form of inverted channels and the top of the tension member merging into an upwardly extending web in the region of the journal box which web extends above the plane of the 85 top of the box and unites the side walls of the compression member and terminates below the top of said member.

90 2. A cast side frame for car trucks having a compression member, a tension member, a journal box, a web rising from the top of the tension member and connecting the side walls of the compression member,

and a rib connecting the journal box with the top of the compression member and with said web.

3. A cast side frame for car trucks having a compression member, a tension member, a journal box, a web rising from the tension member and uniting the side walls of the compression member, and a rib unit-

ing the top of the journal box with the top of the compression member and extending 10 down between and uniting the side of the journal box and said web.

In testimony whereof, we have signed this specification.

GEORGE T. JOHNSON.
HARRY W. STERTZBACH.
